 Filed Dec. 18, 1964, Ser. No. 419,364
 4 Claims. (Cl. 323—123)

This invention relates to signal transmission circuits and, more particularly, to all pass-networks of the type used as phase correctors.

In the transmission of a complex signal waveform, one having a plurality of frequency components within a particular time period, it often happens that the waveform becomes phase distorted. Phase distortion can be minimized by allowing phase to vary directly with frequency. Circuits wherein the phase of the output varies with the frequency of the input are generally known as phase correctors. Phase corrector circuits are particularly useful in television signal processing equipment, in the read-out portion of a magnetic recording system, and in other like systems wherein phase correction is necessary.

Many well-known phase corrector circuits are designed such that they should ideally be connected to a load having an infinite impedance. Practically, it is impossible to obtain a very high or infinite impedance. For example, in a typical video system when the frequency is in the neighborhood of ten megacycles, the stray capacitance of the stage being fed by the phase corrector circuit acts to lower the effective load impedance of the phase corrector circuit.

It is an object of this invention to provide a phase shift from 0 to 180 degrees as the frequency of the input signal varies and to provide a constant gain over the same frequency range.

It is another object of this invention to provide a phase corrector circuit which operates in a current mode as distinct from prior art types which operate in a voltage mode.

It is yet another object of this invention to provide a phase corrector circuit capable of driving a low impedance load.

In accordance with this invention, there is provided a bridge network having first, second and third equal value resistive arms and a fourth reactive arm. A load having a low impedance relative to the value of any one of the resistive arms is coupled between first and second junctions defined by the first and third resistive arms and by the second resistive and fourth reactive arms, respectively. A current generator means responsive to an input waveform having one or more frequency components is provided for applying to a third junction defined by the third resistive and the fourth reactive arms a current whose magnitude is determined by the magnitude of the currents flowing in the first and second resistive arms.

FIG. 1 is a schematic circuit diagram of this invention; and

FIG. 2 is a phase diagram of the currents present in the various branches of the circuit of FIG. 1.

In FIG. 1 a current generator 1 is connected to a bridge network 2 at junctions 3 and 4. Although the current generator 1 is illustrated as an NPN transistor Q having its collector and emitter coupled to junctions 3 and 4, respectively and its base connected to a signal waveform means E_S , it is apparent to those skilled in the art that a PNP transistor could be used. Moreover, the current generator 1 may be any well-known current generating device. For example, the current generator could be a pentode vacuum tube or a field effect semiconductor device.

In the bridge network a resistor R_3 is connected in a

third arm of the bridge between junction 3 and junction 5. The battery V_C is connected in this arm of the bridge to provide operating potential for the transistor Q. A resistor R_1 is connected in a first arm of the bridge between junctions 4 and 5. A resistor R_2 is connected in a second arm of the bridge between junctions 4 and 6. A capacitor C_1 provides the reactive element and is connected in a fourth arm of the bridge between junctions 3 and 6. A load resistor R_L is coupled between junctions 5 and 6 of the bridge. The capacitor C_2 , connected in series with load resistor R_L , is a D.C. blocking capacitor. The load resistor R_L may be the input resistance of a transistor circuit or may be any other suitable utilization device.

The circuit operation can best be understood from a consideration of the currents in the various arms of the bridge 2. The currents I_1 , I_2 , I_3 , I_C and I_L are indicated by their respective arrows in FIG. 1. If the reactance of capacitor C_2 and the resistance of R_L are very small relative to resistance R_2 , substantially all of the signal voltage E_S transmitted through the base to emitter junction of transistor Q appears across R_2 and R_1 in parallel. Consequently, the currents I_1 and I_2 are in phase with input signal E_S and are constant in magnitude relative to the magnitude of E_S . These two currents I_1 and I_2 are summed at junction 4 and applied to junction 3 by the current generator 1. Thus, resistors R_1 and R_2 function as a current source for the current generator.

In the two arms of the bridge coupled to junction 3, resistance R_3 is large relative to the load impedance and capacitor C_1 is small relative to the D.C. blocking capacitor C_2 . For very low values of frequency, the reactance of capacitor C_1 , being large relative to resistance R_3 , acts as an open circuit. Thus, current I_C is nearly zero and current I_3 is equal to the sum of currents I_1 and I_2 . An analysis of the currents flowing into and out of junction 6 reveals that:

$$I_L = I_2 - I_C \quad (1)$$

Since I_C is zero,

$$I_L = I_2 \quad (2)$$

Consequently, load current I_L is in phase with the signal E_S for very low frequencies.

For very high frequencies the reactance of C_1 , being very small relative to resistance R_3 , acts as a short circuit. Consequently, current I_3 is nearly zero and current I_C is equal to the sum of currents I_1 and I_2 . Since I_C is the sum of I_1 and I_2 , Equation 1 may be expressed as:

$$I_L = I_2 - (I_1 + I_2) \quad (3)$$

or

$$I_L = I_1 \quad (4)$$

If current I_1 is equal to current I_2 ($R_1 = R_2$), the gain is constant, i.e., the magnitude of the load current I_L is constant relative to or directly proportional to the magnitude of the input signal waveform. Thus, for $R_1 = R_2$ the load current magnitude is directly proportional to the magnitude of the input signal for all frequencies and the load current phase varies from 0 to 180 degrees as the frequency varies from near zero to near infinite frequency.

FIG. 2 is a phase diagram of currents I_1 , I_2 , I_L and I_C further illustrating the operation of the invention. The vector marked I_1 & I_2 is derived from a reference point G and is considered to be in phase with the input signal. The vector I_L is seen to describe a semicircle having a radius equal to the absolute value of I_1 or I_2 as the frequency increases. When the frequency is zero, the load current vector I_L superimposed on vector I_2 and the capacitor current vector I_C is zero. As the frequency increases, vector I_C increases in magnitude and vector I_L rotates by phase

angle ϕ away from vector I_2 . As the frequency approaches infinity, the phase angle ϕ of vector I_L approaches 180 degrees and vector I_C approaches a magnitude twice the magnitude of vectors I_1 , I_2 and I_L .

The connection of the capacitor C_1 between junctions 3 and 6 is very important and advantageous to the current mode operation of the phase corrector. Due to the constant magnitude of currents I_1 and I_2 for all values of frequency relative to the magnitude of the input waveform, the load current vector also remains constant as shown by Equations 2 and 4 and by the phase diagram in FIG. 2. If capacitor C_1 and resistance R_2 were interchanged, the current magnitude at junction 4 and in the load would not be constant for all values of frequency. In fact the current at junction 4 would be equal to I_1 at zero frequency and would become very large as the frequency increases, resulting in unstable nonlinear operation of the current source. Although a voltage mode phase corrector circuit could be constructed in this manner by making the load impedance very large, the previously-mentioned disadvantage of stray capacity effectively reducing the impedance at the output is encountered.

It is apparent to those skilled in the art that resistors R_1 and R_2 need not be equal. If R_1 is less than R_2 such that I_1 is greater than I_2 , it is evident from Equations 2 and 4 that the load current I_L experiences gain as the frequency increases. Similarly, if R_1 is greater than R_2 such that I_1 is less than I_2 , it is evident that load current I_L is attenuated as the frequency increases.

It is also apparent to those skilled in the art that an over-all voltage gain may be achieved by coupling the load current I_L to the input of a low input impedance amplifier, such as a common base transistor amplifier or any suitable operational amplifier.

What is claimed is:

1. An electrical circuit comprising a bridge network having first, second and third resistive arms and a fourth reactive arm,

a load having a low impedance relative to the value of any one of said resistive arms coupled between first and second junctions defined by said first and third resistive arms and by said second resistive and said fourth reactive arms respectively,

said third resistive and said fourth reactive arms being coupled to a third junction, said first and second resistive arms being coupled to a fourth junction, and

generator means responsive to an input waveform for applying a current to said third junction and a voltage to said fourth junction, said current having a magnitude determined by the sum of the currents in said first and second resistive arms.

2. An electrical circuit comprising a bridge network having first and second equal value resistive arms, a third resistive arm, and a fourth reactive arm,

a load having a low impedance relative to the value of any one of said resistive arms coupled between first and second junctions defined by said first and third resistive arms and by said second resistive and said fourth reactive arms respectively,

said third resistive and said fourth reactive arms being coupled to a third junction, said first and second resistive arms being coupled to a fourth junction, and

generator means responsive to an input waveform for applying a current to said third junction and a voltage to said fourth junction, said current having a magnitude determined by the sum of the currents in said first and second resistive arms.

3. An electrical circuit comprising a bridge network having first, second and third resistive arms and a fourth reactive arm,

a load having a low impedance relative to the value of any one of said resistive arms coupled between first and second junctions defined by said first and third resistive arms and by said second resistive and said fourth reactive arms respectively,

said third resistive and said fourth reactive arms being coupled to a third junction, said first and second resistive arms being coupled to a fourth junction, generator means responsive to an input waveform having a plurality of frequency components within a particular time period for applying a current to said third junction and a voltage to said fourth junction, said current having a magnitude determined by the sum of the currents in said first and second resistive arms,

said generator means including a transistor having its collector and emitter electrodes coupled to said third and fourth junctions, respectively, and means for applying said waveform to the base electrode of said transistor.

4. An electrical circuit comprising a bridge network having first and second equal value resistive arms, a third resistive arm, and a fourth reactive arm,

a load having a low impedance relative to the value of any one of said resistive arms coupled between first and second junctions defined by said first and third resistive arms and by said second resistive and said fourth reactive arms respectively,

said third resistive and said fourth reactive arms being coupled to a third junction, said first and second resistive arms being coupled to a fourth junction, generator means responsive to an input waveform having a plurality of frequency components within a particular time period for applying a current to said third junction and a voltage to said fourth junction, said current having a magnitude determined by the sum of the currents in said first and second resistive arms,

said generator means including a transistor having its collector and emitter electrodes coupled to said third and fourth junctions, respectively, and means for applying said waveform to the base electrode of said transistor.

generator means responsive to an input waveform for applying a current to said third junction and a voltage to said fourth junction, said current having a magnitude determined by the sum of the currents in said first and second resistive arms.

3. An electrical circuit comprising a bridge network having first, second and third resistive arms and a fourth reactive arm,

a load having a low impedance relative to the value of any one of said resistive arms coupled between first and second junctions defined by said first and third resistive arms and by said second resistive and said fourth reactive arms respectively,

said third resistive and said fourth reactive arms being coupled to a third junction, said first and second resistive arms being coupled to a fourth junction, generator means responsive to an input waveform having a plurality of frequency components within a particular time period for applying a current to said third junction and a voltage to said fourth junction, said current having a magnitude determined by the sum of the currents in said first and second resistive arms,

said generator means including a transistor having its collector and emitter electrodes coupled to said third and fourth junctions, respectively, and means for applying said waveform to the base electrode of said transistor.

4. An electrical circuit comprising a bridge network having first and second equal value resistive arms, a third resistive arm, and a fourth reactive arm,

a load having a low impedance relative to the value of any one of said resistive arms coupled between first and second junctions defined by said first and third resistive arms and by said second resistive and said fourth reactive arms respectively,

said third resistive and said fourth reactive arms being coupled to a third junction, said first and second resistive arms being coupled to a fourth junction, generator means responsive to an input waveform having a plurality of frequency components within a particular time period for applying a current to said third junction and a voltage to said fourth junction, said current having a magnitude determined by the sum of the currents in said first and second resistive arms,

said generator means including a transistor having its collector and emitter electrodes coupled to said third and fourth junctions, respectively, and means for applying said waveform to the base electrode of said transistor.
